CLAIM

The ornamental design for a back support and detachable apron, as shown and described.

DESCRIPTION

FIG. 1 is a front elevation view of a back support and detachable apron showing my new design in condition of use attached to a human torso;

FIG. 2 is a right side elevation view, the left side being a mirror image thereof;

FIG. 3 is a right side elevation view shown prior to tying the belt, the left side being a mirror image thereof;

FIG. 4 is a front elevation view of the detachable apron shown separately for clarity of illustration thereof;

FIG. 5 is a front perspective view of the back support shown separately for clarity of illustration thereof;

FIG. 6 is an enlarged perspective view of the back support shown separately in an open condition for clarity of illustration thereof;

FIG. 7 is an enlarged outside perspective view of the back support shown separately in an open condition for clarity of illustration thereof; and,

FIG. 8 is an exploded front perspective view of the back support and detachable apron thereof.

The broken lines shown on the back support and detachable apron in the drawing are understood to represent stitching.

The broken line showing of a human torso is for illustrative purposes only and forms no part of the claimed design.
